UNITED STATES PATENT OFFICE.

GUSTAV A. MERKT, OF WORCESTER, MASSACHUSETTS, ASSIGNOR TO THE AMERICAN STEEL & WIRE COMPANY OF NEW JERSEY, OF HOBOKEN, NEW JERSEY, A CORPORATION OF NEW JERSEY.

RAIL-BOND.

1,154,264.

Specification of Letters Patent. Patented Sept. 21, 1915.

Application filed April 8, 1912. Serial No. 689,202.

REISSUED.

To all whom it may concern:

Be it known that I, GUSTAV A. MERKT, a citizen of the United States, residing at Worcester, in the county of Worcester and 5 State of Massachusetts, have invented a new and useful Rail-Bond, of which the following is a specification.

My invention relates to the construction of rail bonds used in connecting the adjoining ends of the track rails of railways, and 10 the invention more particularly relates to the construction of the type of rail bonds used on electric railways in which the terminals of the rail bonds are welded directly 15 to the surfaces of the rails to which the bonds are applied for use.

Heretofore it has been the practice to bond the adjoining rail ends of the railway tracks by means of copper conductors of 20 various commercial forms. The terminals of such bonds are expanded into or riveted in openings or holes in the track rails, and, with some forms of such rail bonds, the terminals are soldered or welded to the rails. 25 With such bonds the terminals are applied to the rail heads in some cases, to the flanges of the rails in other cases, in addition to the more general practice of applying the terminals to the web of the rails. The conductors, to the ends of which the bond terminals are attached, have sufficient flexibility to permit the unavoidable movement occasioned by the expansion and contraction 30 lengthwise of the rails.

One object of my invention is to provide 35 a rail bond of improved construction having novel means whereby a larger contact surface is afforded on the bond terminals, the contact intensity is increased and by which the bond terminals are more securely anchored or united to the rails and liability of loosening of the bond terminals and of mechanical injury to the contacts is lessened and prevented.

Another object of my invention is to provide 45 a rail bond having improved means whereby a perfect union is obtained between the contacting faces of the rails and the rail bond terminals.

The invention consists in providing a 50 coating or contact on the terminals of the rail bonds, which is formed of a material having substantially the same composition, fusing point and degree of conductivity as that of the rails to which the rail bonds are

welded, as in the case of rails composed of steel, to provide the rail bond with terminals having steel surfaces forming contacts engaging with the rails in welding the terminals to the rails.

My invention is applicable to any of the known types of rail bonds in which the terminals are welded to the track rails or secured thereto in an analogous manner.

Referring to the accompanying drawings 65 Figure 1 is a plan showing the adjoining ends of the track rails having one form of rail bond constructed and arranged and secured in place thereon in accordance with this invention. Fig. 2 is a transverse section of the same taken on the line II-II 70 of Fig. 1. Fig. 3 is a plan showing a modified rail bond construction, having the terminals thereof constructed in accordance with my invention. Fig. 4 is a longitudinal 75 side elevation of the construction shown in Fig. 3. Fig. 5 is a detail sectional side elevation, on an enlarged scale, showing the manner in which the terminals are secured to the conductors and the metal coating is 80 applied to the terminals of the rail bond of Figs. 3 and 4. Fig. 6 is a sectional end elevation on the line VI-VI of Fig. 5. Fig. 7 is a sectional end view of a track rail, showing a splice-bar connected thereto with 85 the rail bond terminals secured to the splice-bar in accordance with this invention. Fig. 8 is a sectional plan, on the line VIII-VIII 90 of Fig. 7. Fig. 9 is a plan showing the adjoining ends of two track rails, with a rail bond applied to the upper faces of the rail flanges. Fig. 10 is a side elevation showing a rail bond constructed in accordance 95 with my invention as applied for use to the lower face of the rail flanges in bonding the track rails.

In the drawings referring to Figs. 1 and 2, the numeral 2 designates the ends of two track rails which are secured together by means of splice bars 3, 3, and bolts 4, and which have a rail bond secured thereto in accordance with my invention. In the form of rail bond shown in these figures a steel ribbon 5 is united with a copper or aluminum ribbon 6 preparatory to attaching the rail bond to the rails. The ends of the conductor formed by the ribbons 5 and 6 are curved or bent so as to bring the steel ribbon 5 thereof with the steel faces of the rail bond in engagement with web of the rails 110.

2. The bonds which are formed in a separate process prior to being applied for use in the track, are then united to the rail webs by welding. In this way, the surfaces of the 5 rail bond contacting with the rails are of substantially the same composition as the rails and having substantially the same electrical conductivity, which permits of the parts being easily heated to the same temperature in welding the parts to attach the 10 rail bond in place on the rails.

In the construction shown in Figs. 3, 4, 5 and 6, a well known form of rail bond is shown in which strands 7 formed of copper 15 wire are connected at their ends to terminals 8 which have a steel plate 9 united thereto by welding or fusing, this plate forming the face of the terminals contacting with and welded to the rail when applied 20 for use, the plate 9 being the same in composition and degree of electrical conductivity as the rail to which the rail bond is applied.

In the construction shown in Figs. 7 and 25 8, a rail bond is applied to the splice bars which connect the rails and in this construction the splice bars 10 are bolted to the flanges 11 of the rails, one end of each splice bar 10 being bolted in contact with the web 30 of one rail with the edges of the other end of the splice bar in engagement with the top surface of the rail flange and the under inclined surface of the rail heads. The rail bond conductor in this construction is 35 formed of a copper wire or rod 12, one end being connected to each of the splice bars 10, as will be seen by reference to Figs. 7 and 8. In this construction the splice bars 10 form the terminals of the rail bond and the 40 ends 10^a of these splice bars are welded to the web of the rail, the bolts 12 being employed to secure the other end of the splice bars 10 to the rail flanges. In this construction it will be seen that the rails can expand 45 lengthwise and at the same time a perfect connection is formed and maintained by the rail bond between the rails as the ends 10^a of the splice bars are welded to the rails.

In the construction shown in Fig. 9 a rail 50 bond is shown having a conductor comprising

ing a ribbon 13 formed of aluminum or copper which is welded or otherwise united with a steel ribbon 14 preparatory to applying the rail bond for use in electrically connecting the ends of the rails 15. In this construction the ends of the ribbon which form the bond terminals are applied to the upper surface of the rail flange with the steel surface of the bond in contact with the rail.

In the construction shown in Fig. 10 a 60 rail bond having a conductor formed of a copper aluminum ribbon 16 with a steel ribbon 17 is employed, the ends of the conductor forming the terminals being secured to the under surface of the flanges of the rails 65 18, and the steel surface of the ends of the bond which forms the terminals being welded to the rails.

From the above description it will be seen that in all cases the rail bonds are provided 70 with a terminal formed of steel or a terminal having a surface formed of metal of the same composition and electrical conductivity as the metal forming the rails which are to be united by the rail bonds.

I believe myself the first to discover and disclose the advantages of providing the terminals of rail bonds with a coating or covering of metal which is united to the terminals and is of the same composition or 80 electrical conductivity as the rails to which the rail bonds are applied, and I intend to claim such construction broadly.

I claim:

A rail bond comprising a conductor and 85 terminals on the ends of the conductor, said terminals being coated with metal of the same chemical composition, having the same fusing point and having the same electrical conductivity as the metal in the rails to 90 which the bonds are applied, the metal coating of the terminals being united therewith, and electrically welded to the track rails.

In testimony whereof, I have hereunto set my hand.

GUSTAV A. MERKT.
